SUCTION ELECTRODE

William W. Welsh, Rockville, Md., assignor to
Bowen & Company, Inc., Bethesda, Md., a corporation of Delaware

Application July 12, 1950, Serial No. 173,348

1 Claim. (Cl. 128—404)

1

This invention relates to suction electrodes and particularly to electrodes constituting a terminal clamp electrically connected to a suction device whereby the terminal clamp may be electrically connected to the skin of a patient for electrocardiographic and similar purposes.

In general the device comprises a terminal clamp to be connected in the circuit or circuits of an electrocardiograph machine, said terminal clamp being in electrical connection with a conductive cup member adapted to contact the skin of the patient. Suitable means are provided for at least partially evacuating the cup member to create sufficient suction to establish good electrical contact between the cup member and the skin of a patient and to hold the device in place.

It is therefore an object of this invention to provide a suction electrode that may be readily and easily applied to the skin of the patient.

It is a further object of this invention to provide a suction electrode capable of establishing firm contact with the skin of a patient without the necessity of employing straps or clamps.

It is a further object of this invention to provide a suction electrode that may be applied to the skin of a patient by a simple manipulation of the device involving only the use of one hand.

It is another object of this invention to provide a suction electrode of unique design and simple and economical construction.

Further objects and advantages will appear as the description proceeds in connection with the accompanying drawings wherein:

Fig. 1 is a vertical sectional view of one embodiment of the present invention.

Fig. 2 is a vertical sectional view of a different embodiment of the invention, and

Fig. 3 is a vertical sectional view of a still further modification.

The modification shown in Fig. 1 comprises a generally hemispherical cup member 2 having an upwardly extending hollow boss 3 integral therewith. The boss 3 is provided with a peripheral finger-engaging flange 4 about its upper end. Preferably, the cup member 2 will be made of a suitable electrically conductive metal and a terminal clamp 5 is rigidly attached to the cup member 2 in any suitable manner, such as by riveting a portion 6 thereof in a countersunk opening through the cup member 2, or by soldering, welding, or the like. The terminal clamp 5 may be provided with a transverse opening 7 and a clamp screw 8 to suitably connect the terminal end of a circuit conductor to the cup 2. Adjacent the mouth of the cup member 2 is an inwardly facing peripheral recess or groove 9 spaced slightly inwardly of the peripheral edge 10 which defines the mouth of the cup member 2. A flexible diaphragm 11 of rubber or the like is provided with a rolled or inturned edge 12 embracing a ring

2

13. The ring 13 is preferably a split ring of resilient material whereby it may be positioned in the recess 9 to clamp the peripheral edge of the diaphragm 11 to the cup member 2 with an air-tight seal, thus defining a flexible partition slightly inwardly of the mouth of the cup member 2.

An integral boss 14 on the diaphragm 11 extends inwardly of the cup member 2 and has attached thereto, by means of pin 15 a suitable actuating plunger 16. The lower end of plunger 16 may, as shown, be embedded in the material of the boss 14. The plunger 16 extends upwardly through an enlarged opening 17 providing communication between the interior of the cup member 2 and the interior of the hollow boss 3. The member 16 extends outwardly through the hollow boss 3 and is attached at its outer end to a hollow cap 18. The cap 18 extends into and is guided by the hollow interior of the boss 3 and houses a suitable compression spring 19. The compression spring 19 abuts at one end against the bottom of the hollow interior of the boss 3 and at its upper end abuts the interior of the cap 18.

In the position shown in Fig. 1, the spring 19 is under compression and normally tends to urge the cap 18, plunger 16, and boss 14 upwardly to draw the diaphragm 11 upwardly into the cup member 2.

30 In use the device of Fig. 1 will first be suitably connected to a conductor, by means of terminal clamp 5, and the cap 18 will be depressed to the position shown in Fig. 1 before application to the skin of a patient. With the parts in the position

35 shown in Fig. 1, the electrode is positioned against the patient's skin at the desired position with the peripheral edge 10 of the mouth of the cup member in snug contact with the patient's skin. After such contact is made, cap member 18

40 may be released whereupon spring 19 will expand and draw the diaphragm 11 upwardly into the cup member 2, thus creating a partial vacuum between the diaphragm 11 and the patient's skin. The partial vacuum thus created will result in

45 the cup member 2 being firmly held, by atmospheric pressure, against the skin of the patient, thus establishing good electrical contact therewith. To release the electrode, it is only necessary to depress the cap 18 to the position of Fig. 1, whereupon the pressure between the diaphragm 11 and the patient's skin will again be raised to substantially atmospheric pressure and the device may readily be lifted from the patient.

Referring now to Fig. 2, the embodiment

55 shown therein comprises a generally cylindrical cup member 20 having a free peripheral edge 21 defining the open mouth thereof. The cup member 20 will also be made of suitable electrically conductive material and is provided with a hollow, upstanding, integral boss 22 having a

60

finger-engaging flange 23 thereon. An opening 24 establishes communication between the interior of the hollow boss 22 and the interior of the cup member 20. A piston 25 having a piston rod 26 is positioned within the cup member 20 with the rod 26 extending through opening 24 into and through the hollow interior of the boss 22. The piston 25 is provided with a suitable peripheral groove 27 receiving a suitable O-ring 28 of rubber or the like. The normal outer diameter of the O-ring 28 is slightly greater than the internal diameter of the cup member 20 whereby the ring 28 is held in radial compression when assembled in the manner shown in Fig. 2. The ring 28 provides an airtight seal between the piston 25 and the cylindrical cup 20.

A cap member 29 is threadedly connected to the rod 26 and is of such diameter and length as to be readily received in and guided by the hollow interior of the boss 22 whereby movement of the cap member 29 downwardly results in driving the piston 25 downwardly within the cup member 20. A suitable compression spring 30 is housed within the hollow boss 22 and abuts at one end against the partition wall between the boss 22 and the cup member 20 and at its other end abuts a downwardly facing shoulder defined by the lowermost end of the cap 29. The compression spring 30 normally tends to assume the position shown in Fig. 2 so that depression of the cap 29 will compress the spring 30. The spring 30 thereby normally urges piston 25 upwardly to the position shown in Fig. 2.

A clamp member 31 of suitable electrically conductive material is firmly connected to the boss 22 to establish electrical contact therewith and may be provided with a split portion 32 and clamp screw 33 whereby an electrical conductor may be clamped thereto in firm electrical contact. Thus the member 31 provides for establishing electrical contact between an external circuit and the conductive cup member 20.

The operation of the embodiment just described in connection with Fig. 2 is identical with the operation described in connection with the embodiment of Fig. 1, that is, after connection to the circuit of an electrocardiograph or other machine, the cap 29 and piston 25 may be depressed, the device may then be placed against the skin of a patient, and upon release of cap 29, spring 30 will move the piston 25 upwardly, thus creating a partial vacuum between the piston 25 and the skin of the patient to utilize atmospheric pressure to hold the peripheral edge 21 of the cup 20 in firm electrical contact with the patient.

The embodiment shown in Fig. 3 comprises a substantially hemispherical cup 35 of conductive material having a peripheral edge 36 defining the open mouth of the cut. A metallic tubular connector 37 having a reduced end portion 38 is attached to the cup member 35 with the reduced end portion 38 extending through an opening in the cup member. The fit between the reduced end portion 38 and the cup 35 may be a tight frictional fit or the reduced end portion may be expanded after assembly or may be soldered or otherwise fastened to the cup member to form a permanent assembly establishing good electrical contact at the joint.

A conductor clamping member 39 surrounds the tubular member 37 and may be substantially identical to the clamp member 31 described in connection with Fig. 2. The clamp member 39

will, however, be in firm electrically conductive contact with the tubular member 37.

A resilient hollow bulb 40 of rubber or like material has an extending neck portion 41 tightly embracing the tubular member 37 outwardly of the terminal clamp 39. The tubular member 37 thus establishes communication between the interior of the flexible bulb 40 and the interior of the cup member 35.

The flexible bulb 40 is sufficiently rigid to normally assume the position shown in Fig. 3 with the generally spherical bulb portion fully extended. In applying the device of Fig. 3, the terminal end of the desired conductor will first be clamped in the clamp member 39 and the operator will then squeeze the bulb 40 to collapse the same, thus expelling a substantial portion of the air therein through the tubular member 37 and outwardly of the cup member 35. While the bulb is maintained in such collapsed condition, the cup member 35 is engaged with the skin of the patient by firmly pressing the peripheral edge 36 against the patient's skin. While being so held, the bulb 40 is released and will expand to the position of Fig. 3 due to its own resiliency, thus creating a partial vacuum within the cup member 35 and again utilizing atmospheric pressure to maintain the cup member 35 in firm electrical contact with the patient. To release the device it is necessary only to squeeze the bulb 40 to collapse the same, whereupon the entire electrode may be readily lifted from the patient.

While a limited number of specific embodiments of the invention have been shown and described herein, it is to be understood that the invention is not limited thereto but encompasses all modifications falling fairly within the scope of the appended claim.

I claim:

A suction electrode comprising, a cup member of electrically conductive material, said cup member being in the shape of a spherical segment no greater than a hemisphere and having a smooth terminal edge defining an open mouth, a tubular member of electrically conductive material fixed to said cup member and extending therefrom in a direction away from said open mouth, the interior of said tubular member communicating with the interior of said cup member, a terminal clamp fixed to said tubular member, and a hollow resilient bulb having a short integral neck portion embracing said tubular member with the interiors thereof in communication whereby to provide an air passageway between the interiors of said bulb and cup member; said terminal clamp being provided with an opening through which said tubular member extends with a tight fit and being closely adjacent said cup member, said neck portion of said bulb abutting said terminal clamp whereby to maintain the overall length of said electrode at a minimum.
